UNITED STATES PATENT OFFICE

1,926,930

BOILER CLEANING APPARATUS

Charles Bacher, New York, N. Y.

Application February 1, 1933. Serial No. 654,747

1 Claim. (Cl. 122—390)

This invention relates to boiler cleaning apparatus.

The invention will be fully and comprehensively understood from a consideration of the following detailed description when read in connection with the accompanying drawing which form part of the application, with the understanding, however, that the improvement is capable of extended application and is not confined to the exact showing 10 of the drawing nor to the precise construction described and, therefore, such changes and modifications may be made therein as do not affect the spirit of the invention nor exceed the scope thereof as expressed in the appended claim.

15 The drawing shows in front elevation the boiler having the usual equipment for blowing air into the boiler and also shows the apparatus of my invention connected with the usual air blowing apparatus.

20 The numeral 5 indicates a boiler, into the lower part of which, below the grate, air is blown by a blower 7 thru a pipe 8. A receptacle 9 for receiving material cleaned from the boiler tubes is connected by means of a pipe 10 to the pipe 8. A 25 valve 12 is positioned in the pipe 8 between its point of connection with the pipe 10 and the boiler. A valve 15 is provided in the pipe 10. The latter pipe has an opening shown as closed by cap 17. The air inlet side of the blower 7 is 30 covered with a screen 18 and on this screen is placed a semi-circular member 20, which carries a pipe 21 to which is connected a flexible hose 23, the other end of said hose being connected to a pipe 24 which has a rubber cup 25 attached to its 35 free end.

When the tubes of the boiler are to be cleaned, the valves 12 and 15 are closed and opened respectively and the cup 25 is placed against the end of the tube or a series of tubes to be cleaned. The material removed from the tubes then passes 60 thru the pipe 24 of the flexible hose 23 and the pipe 21, thru the blower part of the pipe 8 into the pipe 10 and then into the receptacle 9. When it is desired to force air thru the tubes of the 65 boiler or to clean other parts of the boiler, the cap 17 is taken off the pipe 10 and the hose 23 is fitted over the opening normally closed by the cap while the valves 12 and 15 are closed. The blower then blows air through part of the pipe 8 and part of the pipe 10 and forces it into the 70 hose 23 and the pipe 24, the cup 25 being placed at a point where it is desired to have the air pressure.

What is claimed is:

The combination with a tube boiler and its setting, of a blower, a pipe connecting said blower with the lower part of the boiler setting for conducting air under pressure from the blower to the combustion space of said boiler setting, a receptacle, a second pipe connected to the first-mentioned pipe and to the receptacle, a valve in said first pipe between the boiler setting and the point of connection of the second pipe, a valve in the second pipe, the second pipe having a capped opening between the valve therein and the connection of the second pipe with the first mentioned pipe and a detachable tube leading from the air inlet end of the blower and adapted to be placed at the ends of the boiler tubes.
